UNITED STATES PATENT OFFICE.

WILLIAM A. KÖNEMAN, OF CHICAGO, ILLINOIS, ASSIGNOR OF ONE-HALF TO
AZEL F. HATCH, OF CHICAGO, ILLINOIS.

PULVERIZING APPARATUS.

SPECIFICATION forming part of Letters Patent No. 740,764, dated October 6, 1903.

Application filed July 30, 1902. Serial No. 117,648. (No model.)

To all whom it may concern:

Be it known that I, WILLIAM A. KÖNEMAN, a citizen of the United States, residing at Chicago, in the county of Cook and State 5 of Illinois, have invented a new and useful Improvement in Pulverizing Apparatus, of which the following is a specification.

My invention relates to improvements in pulverizing-machines of the class employing 10 an axially-rotating bed or crushing plate of frusto-conical form and a series of radially-disposed frusto-conical crushing-rollers upon the bed-plate, the material to be pulverized being fed upon the center of the rotating bed-plate and caused to pass beneath the rollers.

My object is to provide various improvements in the construction of pulverizing-machines of this class with a view to diminishing the number of parts and simplifying the 20 construction, operation, and maintenance thereof and to render the machine more perfect and better adapted for the purpose of rapidly reducing material fed thereto to a desired fine state of pulverization.

Referring to the drawings, Figure 1 is a top plan view of one half the machine, the other half (not illustrated) being virtually a duplication of the parts shown; Fig. 2, a plan section of one half the machine, taken from the 30 angular line 2 in Fig. 12, on a reduced scale; Fig. 3, a broken plan section taken on line 3 of Fig. 4; Fig. 4, a central vertical section taken on line 4 in Fig. 1; Fig. 5, a broken detailed plan view of discharging-conveyer 35 mechanism for the pulverized material; Fig. 6, an enlarged broken vertical section through the bearing mechanism for the rotating crushing-bed, the section being taken on line 6 in Fig. 7; Figs. 7 and 8, sections on lines 7 and 40 8 of Fig. 6; Fig. 9, a perspective view of a cushioned pillow or bearing-seat shown in Fig. 6; Fig. 10, an enlarged broken section on line 10 in Fig. 1 through one of the frusto-conical crushing-rollers and its bearing and 45 adjusting mechanism; Fig. 11, a section taken on line 11 in Fig. 10; Fig. 12, a broken and enlarged section on line 12 in Fig. 1, and Fig. 13 a broken section taken on line 13 in Fig. 12.

A is an octagon foundation of stone, concrete, or other material forming a central pit A'.

B is a rotary crushing-bed consisting of a hollow box-spider presenting the annular inclined upper plate a, lower plate b, all internally braced, and central hub c. The crushing-bed B is upon the upper end portion of and carried by a vertical shaft C. The box-spider rests upon a collar d on the said shaft and is fastened against independent rotation by a key d'. The supporting-bearing for the 55 shaft C is shown in detail in Figs. 6, 7, and 8.

D is a hollow bed-block or bearing-base presenting a central cylindrical pocket or chamber e. Fitting the pocket e is an annular flanged sleeve-piece or pillow-block D', resting at its flange on a series of stiff coiled springs D² in the pocket e. The shaft C is formed along its lower or bearing end portion with a series of bearing-rings d². On the base-block D and fastened thereto by means of 65 bolts f is a ribbed casing E, formed of two members or halves fastened together by means of bolts f'. The casing E is formed with an annular sleeve portion E', having vertical recesses f² in opposite sides.

E² is a step-box extending through the cylindrical portion E' of the casing. The step-box is formed of two or more segmental members or sections having vertical flanges or feather members f³, fitting the recesses f² in 75 the sleeve E'. The lower end of the step-box is formed with a flange f⁴, resting upon the cushioned pillow-block D'. The box E² is sufficiently loose in the sleeve E' to permit the box to slide vertically. The step-box is 80 formed with a series of annular bearing-recesses f⁵, registering with the rings d² on the shaft C, around which the box fits. The shaft 85 C, carrying the rotating crushing-bed B, rests at its bearing rings or flanges d² in the bearing-recesses f⁵ of the step-box E², which in turn rests upon the pillow-block D', which is cushioned by the springs D². The rings d² present a combined bearing area for the shaft in the bushing, which is comparatively large, 90 and therefore effective in reducing wear in the rotation of the shaft in the step-box. In the space bounded by the pillow-block D' are a series of superimposed case-hardened step-buttons D³, arranged in a common manner, 95 which limit the downward movement of the shaft C.

It has been the practice hitherto to cause the crusher-bed-supporting shaft to rest altogether upon the step-buttons. This is objectionable, because the ingress of dirt or great pressure and insufficient oiling causes friction, which in certain instances has heated the parts to a degree sufficient to weld the buttons, thus necessitating stoppage and expensive repairs. In the present construction nearly all the weight of the crusher-bed and shaft is carried by the bearing-rings rotating in the cushioned step-box, which relieves the pressure on the step-buttons and overcomes the objections to the old constructions referred to.

On the under side of the rotary crushing-bed B is an annular rack B', having an inclined face.

F F are independent drive-shafts extending horizontally through openings in the base A. The shafts are journaled at their inner ends in bearings or plumber-blocks F', mounted in the pit A' or otherwise, and they are journaled toward their outer ends in suitable bearings F², beyond which they carry drive-pulleys F³. On the shafts F adjacent to the bearings F' are bevel-gears F⁴, engaging the rack B'. The upper face of the top plate a of the rotating box-spider presents an inclined annular receiving-face a' and around the same a recessed face portion a². Fitting the recessed portion a² is an annular crushing wearing-plate B², securely fastened in place by bolts a³. The wearing-plate B² forms the crushing-surface portion of the crushing-bed and presents an inner annular face portion g, forming a continuation of the surface a' in the same plane thereof, and an outer annular surface g', pitching downward at a slight angle to the surfaces a' g.

In the present machine I show and prefer to employ eight crushing-rollers G equidistant apart. Each roller G has a head G' of frusto-conical shape, from the larger end of which extends a shank or shaft portion G², provided with a series of integral bearing flanges or rings G³. Surrounding the head G' is an annular frusto-conical wearing-jacket G⁴, which fits closely upon the head and is held in place by a disk h, fastened against the end of the head by bolts h', passing entirely through the head, as shown most plainly in Fig. 10. A description of one roller and attendant parts describes them all.

Anchored upon the base A by means of bolts or otherwise are eight radially-disposed standards or external bearing-casings H, presenting vertical side guide-walls i, provided at their upper ends with radially-inward-extending channel bars or arms i', fitting against and bolted to the arms i' of the next adjacent standards or casings to form practically a continuous frame or structure. Extending between the arms i' of each standard are outer and inner horizontal brace-bars i² i³. The inner ends of the arms i' carry and are

braced by a vertical octagonal thimble or mouthpiece I, having radial lugs I', Fig. 12, which fit into the pockets formed by the channel-bars and are held in place by the bolts i⁴, which hold the channel-bars together, as described. Anchored in the base A at the centers of the standards H are nuts k, in which are vertical jack-screws K, with hand-wheels K' fixed thereon. In each casing H is a vertically-adjustable support H', having a base-plate K², provided in the center of its under side with a socket k', receiving the upper end of the screw K and resting upon the hub of the hand-wheel K'. The screw K is provided in its upper end in the socket k' with an annular recess k² to receive a cotter pin or key k³, driven through an opening in the socket portion k', which key fastens the screw K and vertically-adjustable support H' together without interfering with the turning of the screw. Resting in recesses k⁸ in opposite sides of the follower-plate K² are vertical bearing-plates K³, forming the sides of the support H' and extending parallel with and adjacent to the casing sides i.

K⁴ is a journal-box provided midway between its ends on opposite sides with trunnions k⁴, journaled in circular bearing-recesses k⁵ in the vertical plates K³. Fitting upon the journal-box and removably fastened thereto by means of bolts is a journal-box cover k⁶. The box and cover together present a longitudinally-cylindrical opening which is fitted with a liner or bushing k⁷. The bushing is formed of segmental members, so that the upper part may be removed in the removal of the cap k⁶. The bushing presents a series of thrust-bearing recesses to receive the bearing-rings G³ of the roller-shaft G². Each roller G is in more or less close relation to the surface g' of the crushing-bed, the angle of taper of the surface of the wearing-cone G⁴ being the same as that of the surface g' when the shaft G² extends in the horizontal plane. Each casing H has an inner removable plate i⁵, fastened in place by means of bolts and having an opening for the shaft G² and an outer plate i⁶. On the plate i⁶ is a bracket i⁷, recessed on its upper side to form a seat for a helical spring l. In the under side of each journal-box K⁴ is a dovetailed recess l' to receive a dovetailed plate or arm l², which passes through an opening in the outer plate i⁶ and carries at its outer end an inverted cup l³. Passing downward through the cup l³ is an adjusting-screw l⁴, provided at its lower end with a follower l⁵, forming a bearing for the upper end of the spring l.

As before stated, each roller G extends at its surface G⁴ along the larger end portion of the roller close to the surface g', with which it conforms; but the rollers are externally supported in the sense that their supporting journal-bearings are outside the circumference of the crushing-bed.

A bar K⁵, fastened at opposite ends to the

plates K^3 , close to the side i^5 of the standard or casing, forms a rest for the end of the journal-box K^4 when swung to the horizontal plane. As before stated, the follower-plate K^2 is inseparably fastened to the screw K by the cotter-pin k^3 , and this with the trunnion bearing-plates K^3 and stop-bar K^5 thereon insure the position of the roller in the horizontal plane at all times in the raising and lowering of the journal effected by the jack-screw. Thus the proper angle between the surfaces of the crushing-rollers and crushing-bed is always maintained. The pressure exerted by the roller upon the surface g' may be that of the weight of the roller supplemented by the pressure of the spring l , and the tension of the spring may be increased or diminished by means of the screw l^4 . An adjustment to increase or diminish the pressure of the roller or to take up wear between the surfaces G^4 g' may be effected by turning the jack-screw K to raise the entire support H' . Should a wearing-cone G^4 become worn sufficiently to render its replacement necessary, the screw l^4 may be loosened to raise the follower l^5 and permit removal of the spring l , the plate i^5 may be removed, and the plate i^2 and attendant parts may be withdrawn, after which the roller and its journal-box may be swung in the support H' on the trunnions k^4 to the position shown by dotted lines in Fig. 10, giving ready access to the parts. Should it become necessary to remove the wearing-plate B^2 , all the rollers may be loosened, as described, and raised on their trunnions to give free access to said plate. As before stated, the plate B^2 is fastened in position by means of bolts a^3 , which carry nuts on the underside of the top plate a . Access to these nuts may be had through hand-holes b in the plate portion b .

The thimble I of the frame described presents an octagonal opening m , closed by a cap L with an opening in its center to receive a vertical feed-pipe L' , surmounted by a hopper L^2 . Fastened upon the hub portion of the rotary crushing-bed over the end of the shaft C is a conical deflector M , the pointed upper end of which is at the center of the pipe L' . Slidably mounted in the guide formed by the opening m is an octagonal hopper-shaft support N , provided at its upper end with inward-projecting ears n , presenting vertical threaded openings to receive bolts n' , passing downward through the cover L . The bolts n' thus sustain the supporting-piece N , which may be raised or lowered in the guide m by turning the said bolts. Above each roller G , extending in the direction longitudinally with and parallel to the surface of the wearing-cone G^4 , is a housing P , provided on its upper side beneath the braces i^2 i^3 with sockets p , receiving the lower ends of vertical rods P' , threaded along their upper end portions. The rods are pivotally secured at their lower ends in the sockets p' , having circumferential recesses p' therein engaged by cotters p^2 , extending through the socket-pieces, as shown in Fig. 13. The threaded portions p^3 of the rods pass through threaded sleeves or nuts p^4 on the braces i^2 i^3 , the rods being provided at their upper ends with hand-wheels P^2 . The housing P is of segmental shape in cross-section, having a series of parallel ribs P^3 on its under side conforming to the adjacent roller-surface and extending over and down opposite sides thereof a distance approximating or slightly exceeding one-half the diameter of the roller, all as shown in Fig. 13. The ribs of the housing are close to but out of contact with the surface of the wearing-cone G^4 .

On the base A between the casings or standards H are radially-disposed bearing-blocks Q , having flanged bases q with elongated openings q' therein to receive anchoring-bolts q^2 , fastened in the base A . Extending through each bearing-block Q is an opening q^3 , preferably triangular in cross-section, to receive a bar Q' , also triangular in cross-section. At its opposite or inner end each bar Q' passes through a triangular opening n^2 in the support N , in which it may be fastened by a pin n^3 , as indicated in Fig. 12. On each bar Q' is a rigid collar or shape-block q^4 , retarding guard-blades Q^2 , separated by spacing-washers q^5 , and a sliding collar or shape-block q^6 , the parts being held in rigid relation by bolts q^7 , passing through the shape-block q^6 , blades Q^2 , spacing-washers q^5 , and collar q^4 , as shown in Figs. 12 and 13. The blades Q^2 are shaped with straight upper and lower edges and circular end edges q^8 . The upper edges of the blades Q^2 are close to the lower edges of the housings P^3 , and their lower edges are in a plane parallel with the lower lines of the wearing-cones G^4 close to the bed along the surface g' . The ends q^8 of the blades conform with and are close to the surfaces of the adjacent rollers. The shape-blocks q^4 q^6 present spirally-extending surfaces, and the blades Q^2 and spacing-washers are tightly clamped by the bolts q^7 in such a way that the blades extend in a spiral direction, as indicated in Fig. 2. The bars Q' are adjustably fastened in the blocks Q by means of set-screws q^9 , and the blades may be adjusted with relation to the surfaces of the crusher-bed and crusher-rollers by shifting the block Q upon the bolts q^2 and by raising or lowering the support N by means of the bolts n' .

At the outer circumference of the top plate a^2 of the crushing-bed is an overhanging lip a^4 . R is a U-shaped trough extending entirely around the rotating crusher-bed B and having a low side, which extends underneath the annular lip a^4 , and a high outer side, as shown. The trough forms a series of hoppers R' , between the rollers beneath the bars Q' , having downward-projecting spouts R^2 . Beneath two of the spouts R^2 is a conveyor-trough S , terminating at its end and emptying into a conveyor-trough S' at right angles

thereto and beneath the next two spouts R^2 . The trough S' at its opposite end terminates over and discharges into a long trough S^2 , which also extends beneath two spouts R^2 , 5 and a conveyer-trough S^3 extends beneath the remaining two spouts R^2 and at its end terminates over and discharges into the trough S^2 . In the trough S is a shaft S^4 , carrying a spiral conveyer-blade S^5 . In the trough S^2 is 10 a shaft S^6 , carrying a spiral conveyer-blade S^7 . In the trough S' is a shaft S^8 , carrying a conveyer-blade S^9 , and in the trough S^3 is a shaft S^{10} , carrying a conveyer-blade S^{11} . On the shaft S^4 is a drive-pulley S^{12} , the shafts 15 S^4 S^6 being geared together by a drive-chain S^{13} . On the shaft S^8 is a drive-pulley S^{14} , and the shafts S^8 S^{10} are geared together by a drive-chain S^{15} . The conveyer-trough S^2 has 20 a discharge-outlet S^{16} .

20 The crusher-bed B is necessarily very large and heavy, and being supported entirely from the central vertical shaft C it is a matter of great importance that the bearings for the shaft should be so constructed that there will 25 be a minimum degree of wear thereon in operation. The shaft-rings d^2 , rotating in the recesses f^5 of the step-box E^2 , present a relatively large bearing area and hold the shaft with great steadiness, so that such wear as 30 occurs is distributed equally upon the bearing-surfaces. As shown and described, two drive-shafts F are employed, with beveled drive-gears thereon which engage the rack B' at opposite sides of the bed. This construction 35 tends to distribute the driving pressure to opposite sides of the crusher-bed and balance it in a manner to prevent uneven wear of the shaft C in the step-bearing. The crushing-rollers G and crusher-bed surface g present 40 gradually-diminishing openings or admission-spaces to receive the material to be pulverized, and the material fed to the machine through the hopper L^2 should be through preliminary crushing or otherwise no larger 45 than will freely enter the said spaces.

In operation the bed B is rotated from the shafts F at a desired speed, and by frictional contact between the annular surface g' and rollers G the latter are rotated on their axes. 50 The material to be pulverized fed into the hopper L^2 is distributed with more or less uniformity around the surface a' by the conical deflector M . As the material rolls or slides down the surface a' it is prevented 55 from passing along opposite sides of the rollers by the first spirally-disposed guard-blades Q^2 . These blades in the rotation of the crusher-bed guide the material to be pulverized initially into the open spaces presented 60 at the small ends of the rollers, as described, where the coarser material is initially acted upon, while that portion which is smaller is fed along. While the material is being crushed, it tends, owing to the centrifugal force and 65 the slant of the crusher-bed, to work its way toward the circumference of the bed. The

guard-blades cause the material in its movement to pursue a spiral course, so that it passes from one roller to the next, first in the gradually-reducing spaces at the smaller ends 70 of the rollers over the part g of the bed and then between the rollers and part g' of the bed, which are so close together as to effect the final desired fineness of pulverization. The housings P stop any pulverized material 75 thrown up by the rollers, and the ribs P^3 prevent the rollers from throwing material longitudinally of the rollers. A stream of material to be crushed of the capacity of the inlet-spout L' will result in a continuous discharge 80 of the material finely pulverized around the entire area of the crusher-bed into the annular trough or series of hoppers R R' . As the material falls through the spouts R^2 it enters the conveyer-troughs S S' 85 S^2 S^3 and is moved quickly to the outlet S^{16} , whence it is discharged. The crushing pressure exerted upon the material to pulverize it is the weight of the rollers G supplemented by the pressure of the springs l . Thus the 90 pulverization is effected between a rotary substantially unyielding but cushioned bed and yielding rollers, which will give way slightly when the resistance of the material to pulverization increases to prevent clogging 95 of the machine or undue strain upon its parts. Should a comparatively large piece of metal or other tough material be inadvertently fed into the machine, the yielding rollers will permit it to pass through without 100 working injury.

It is a matter of great importance that the retarding guard-blades described should be properly adjusted with reference to the crusher bed and rollers and be held rigidly 105 in adjusted position. The triangular bars Q' and collars and washers thereon operate to hold the blades Q^2 firmly against the pressure of the material passing through the machine to guide the same, as described, and the said 110 blades may be adjusted with reference to the crusher bed and rollers. The adjustment may be effected by raising or lowering the support N by means of the screws n' , as described, and by shifting the supports Q at 115 their elongated openings q' on the anchoring-bolts q^2 . To permit the sliding of a support Q to raise the bar Q' at that end, the set-screws q^9 may be loosened.

The housings P may be adjusted with reference to the rollers G by turning the hand-wheels P^2 to raise or lower the supports P on the brace-bars i^2 i^3 .

To change the adjustment of the rollers G with reference to the crushing-bed, the hand-wheels K' may be operated to raise the boxes K^4 and all parts carried thereby. Thus the degree of fineness to which the material is to be pulverized may be regulated by raising or lowering the crushing-rollers in the manner 130 described.

The machine constructed as described is

very strong, steady, and durable and has great capacity. The material fed thereto may be pulverized to any desired degree of fineness, and as all the material must pass a number of times between the rollers and crushing-bed the pulverization will be practically uniform.

The machine may be employed to simultaneously pulverize and mix different solid materials fed thereto in a dry or wet state, and the solid constituent product may have any degree of fineness desired. Any percentage of liquid may be fed with the solid material into the machine, whereby the product may be delivered in a plastic or more or less fluent state, as desired.

While I prefer to construct my improvements throughout as shown and described, they may be variously modified in the matter of details of construction without departing from the spirit of my invention as defined by the claims.

What I claim as new, and desire to secure by Letters Patent, is—

25 1. In a pulverizing apparatus, the combination with the stationary base and rotary crushing-bed, of a series of radially-disposed stationary standards on the base about said crushing-bed, said standards being secured together to form a rigid frame on the base, roller-supports in the said radially-disposed standards, raising and lowering means for the said supports in said standards, a series of horizontally-disposed crushing-rollers 35 above the crushing-bed having outward-projecting shafts, and journal-boxes for said shafts pivotally mounted in said supports to swing in the vertical plane in the standards.

2. In a pulverizing apparatus, the combination with the stationary base and rotary crushing-bed, of a stationary standard on the base at one side of said crushing-bed, a roller-support in said standard having a base-plate and side plates formed with trunnion-bearings, a nut fixed in the base of the standard, a vertical jack-screw working in said nut and pivotally secured at its upper end to said base-plate, a crushing-roller above the crushing-bed having an outward-projecting shaft, a 45 journal-box for said shaft pivotally mounted at opposite sides in said trunnion-bearings, and a stop on the support limiting the downward movement of the roller on said trunnions.

55 3. In a pulverizing apparatus, the combination with a stationary base and rotary crushing-bed, of a stationary standard on the base at one side of said crushing-bed, a roller-support in said standard having a base-plate, and side plates formed with trunnion-bearings, a nut fixed in the base of the standard, a vertical jack-screw working in said nut and pivotally secured at its upper end to said base-plate, a crushing-roller above the crushing-bed having an outward-projecting shaft, a 65 journal-box for said shaft pivotally mounted

ed at opposite sides in said trunnion-bearings, a stop on the support limiting the downward movement of the roller on said trunnions, and a spring on the support bearing 70 against the under side of said journal-box beyond the trunnions, whereby in the adjustment of the support the roller-shaft is maintained in a horizontal position, substantially as set forth.

75 4. In a pulverizing-machine, the combination with a stationary base, rotary crushing-bed and crushing-roller above the crushing-bed having an outward-extending shaft, of a journal-box in which said shaft is mounted to 80 rotate, provided on opposite sides with trunnions, a journal-box support having bearings for said trunnions, a jack-screw on which said support is mounted working through a nut on the said base, a spring bearing on the 85 support, a removable and replaceable spring bearing on the under side of the journal-box projecting beyond the outer end thereof, a spring confined between said spring-bearings, and a stop on the support beneath the inner 90 end of said journal-box, all constructed and arranged to operate substantially as and for the purpose set forth.

5. In a pulverizing apparatus, the combination with the supporting-base, rotary crushing-bed, and horizontally and radially disposed crushing-rollers above the bed, of radially-disposed standards on said base joined together to form a frame, a central and vertically-adjustable support on said frame 100 above the crushing-bed, radially-adjustable supports mounted on the base between said standards, supporting-bars mounted at their inner ends in said central support and at their outer ends in said radially-adjustable supports, and a series of spirally-disposed retarding guard-blades on each of said bars extending close to the crushing-bed between the said crushing-rollers, substantially as described.

105 6. In a pulverizing apparatus, the combination with the supporting-base, frame upon the base, rotary crushing-bed bounded by the said frame, and series of horizontally and radially disposed crushing-rollers journaled in the said frame, of housings mounted in the 110 frame above the said rollers and extending over and down opposite sides of said rollers, substantially as and for the purpose set forth.

115 7. In a pulverizing apparatus, the combination with the supporting-base, frame upon the base, rotary crushing-bed bounded by the said frame, and series of horizontally and radially disposed crushing-rollers journaled in the said frame, of housings mounted in the 120 frame above the said rollers and extending over and down opposite sides of said rollers, said housings being formed with series of parallel ribs on their under faces, substantially as and for the purpose set forth.

125 8. In a pulverizing apparatus, the combination with the supporting-base, frame upon

the base, rotary crushing-bed bounded by the
said frame, and series of horizontally and ra-
dially disposed crushing-rollers journaled in
the said frame, of vertically-adjustable hous-
5 ings mounted in the frame above the said
rollers and extending from said supports over
and down opposite sides of said rollers, said

housings being provided on their under faces
with series of parallel ribs, substantially as
and for the purpose set forth.

WILLIAM A. KÖNEMAN.
